UNITED STATES PATENT OFFICE.

MARSHALL BIDWELL SARGENT, OF INDIANAPOLIS, INDIANA, ASSIGNOR TO THE STENOTYPE COMPANY, OF INDIANAPOLIS, INDIANA.

TYPE-WRITING MACHINE.

1,149,087.

Specification of Letters Patent.

Patented Aug. 3, 1915.

Application filed June 18, 1914. Serial No. 845,888.

To all whom it may concern:

Be it known that I, MARSHALL B. SARGENT, of Indianapolis, in the county of Marion and State of Indiana, have invented 5 certain new and useful Improvements in Type-Writing Machines; and I do hereby declare the following to be a full, clear, and exact description of the invention, such as will enable others skilled in the art to which 10 it appertains to make and use the same.

This invention relates to improvements in typewriting machines and more particularly to paper feeding devices; especially to such as are adapted for use for moving the 15 paper strip in a stenographic writing machine,—the object of my present invention being to provide the fingers of the feeding mechanism with separable pawls which may be easily inserted or removed or adjusted.

20 A further object is to provide removable feeding pawls which may be sharpened at both ends, so that when one end of a pawl becomes dulled, it may be inverted to bring the other end in operative position.

25 With these and other objects in view, the invention consists in certain novel features of construction and combinations of parts as hereinafter set forth and pointed out in the claim.

30 In the accompanying drawings, Figure 1 is a sectional view showing a portion of a typewriting machine and illustrating an embodiment of my improvements, and Fig. 2 is an enlarged sectional view showing one 35 of the feeding fingers.

1 represents a portion of the frame of a stenographic typewriting machine, wherein a plurality of key-levers such as indicated at 2 are pivotally supported and provided 40 with upwardly projecting arms 3.

Type-levers 4 are pivotally mounted between their ends and pivotally connected at their lower ends with the upwardly projecting arms 3 of the key-levers, the upper 45 ends of said type-levers being provided with type 5 to engage a paper strip 6 passing in front of a platen 7 carried by a platen frame 8.

The platen frame is provided with rollers 50 9 over which the paper passes and with rearwardly projecting arms 10 pivotally connected at their rear ends to a yoke 11, mounted on the frame 1.

A rock-shaft 12 is mounted in the yoke 11 55 and provided at its ends with rigid arms

such as indicated at 13, each having a spring actuated feeding finger 14 mounted at its upper end, the biting lower portion of which normally rests (when no paper is in the machine) upon the slightly curved upper 60 surface 15 of enlargements 16 formed or made rigid with the rock-shaft 12.

The paper strip 6 passes over the surfaces 15 and under the biting ends of the feeding fingers so that when the shaft 12 is rocked 65 in one direction to cause the arms 13 to move backwardly, the paper will be gripped between said fingers and the surfaces of the lugs 16 are moved or fed as these parts move backwardly. When the shaft 12 rocks forwardly to return the parts to normal positions after having fed the paper, retrograde movement of the paper strip will be prevented by the action of a spring-actuated finger 18 having its biting lower end disposed over a lug 19,—said finger being slightly inclined and coöperating with the upper surface of said lug in a manner to grip the paper. The finger 18 is mounted in arms, such as indicated at 20, projecting 70 forwardly from the cross bar 21 of the yoke 11 and the lug 19 projects forwardly from a plate 22 fixed to the yoke 11 and spaced from the cross-bar 21.

Each spring-actuated finger 14—18 is 75 made in its lower portion with a socket 22 to receive a removable pawl 23 which forms the biting end of the finger, each pawl being beveled at each end to form biting edges 24 and each pawl is held removably in place 80 by means of a set screw 25. A handle or finger piece 26 projects upwardly from each finger 14—18 to facilitate the turning of the finger when it is desired to adjust, remove 85 or insert the pawl or biting member 23.

By providing removable pawls for the fingers as above described, the biting ends of the fingers may be easily adjusted, and removed when worn and inverted or replaced by new pawls, and furthermore, the necessity of making the entire finger of tool steel may be obviated, thus simplifying and cheapening the cost of manufacture.

For the purpose of oscillating the rock-shaft 12 to effect the feeding of the paper 105 when the key-levers are operated, an arm 27 depending from said rock-shaft is connected by a coiled spring pitman 28 with a rocking frame 29 actuated by the key-levers.

Having fully described my invention what 110

I claim as new and desire to secure by Letters-Patent, is:

Paper feeding mechanism comprising an oscillatory member, a member having a gripping face, and a spring-actuated finger, said finger comprising a body portion revolvably mounted on said oscillatory member, a hardened tooth removably attached to said body portion and coöperable with said gripping face, and a handle portion projecting

upwardly from said body portion of the finger.

In testimony whereof, I have signed this specification in the presence of two subscribing witnesses.

MARSHALL BIDWELL SARGENT.
